UNITED STATES PATENT OFFICE

JOHN C. TALIAFERRO, OF BALTIMORE, MARYLAND, ASSIGNOR, BY MESNE ASSIGNMENTS, TO CONTINENTAL CAN COMPANY, INC., A CORPORATION OF NEW YORK.

CAN-CLOSING MACHINE.

1,249,853.

Specification of Letters Patent. Patented Dec. 11, 1917.

Application filed October 23, 1911. Serial No. 656,277.

To all whom it may concern:

Be it known that I, JOHN C. TALIAFERRO, a citizen of the United States, residing at Baltimore, in the State of Maryland, have 5 invented certain new and useful Improvements in Can-Closing Machines, of which the following is a description, reference being had to the accompanying drawing and to the letters and figures of reference marked 10 thereon.

The invention relates to new and useful improvements in can closing machines, and more especially to machines of this type for securing a cover to a filled can by a rolled 15 double seam.

An object of the invention is to provide means for placing a cover on the can body and temporarily securing the same thereto, prior to the feeding of the can body to the 20 seaming head.

A further object of the invention is to provide means for depressing the floating contents in the filled can prior to the placing of the cover thereon and securing the same 25 to the can body.

A further object of the invention is to provide a seaming mechanism with devices operating in unison therewith, whereby a can body is centered, a cover placed on the 30 can body and clenched thereto prior to the feeding of the can body underneath the seaming head.

A further object of the invention is to provide a seaming head with devices operating 35 in unison therewith, for feeding can bodies to the seaming head, devices for depressing the floating contents in the can body, devices for placing the cover on a can body and devices for centering the can body underneath 40 the cover-applying and clenching means.

These and other objects will in part be obvious, and will in part be hereinafter more fully described.

45 In the drawings which show by way of illustration one embodiment of the invention,—

Figure 1 is a front view, partly in section, showing a portion of a head-seaming machine with my improvements applied thereto;

Fig. 2 is a plan view partly in section of the head-applying devices, and the devices for depressing the floating contents of the 55 filled can;

Fig. 3 is a detail in side elevation of the devices for centering the can body, placing the cover thereon and clenching the cover to the can body;

Fig. 4 is a front view, partly in section, 60 of the supporting head for the cover, and the devices for clenching the cover of the can body;

Fig. 5 is a similar view, showing the clenching members in a different position; 65

Fig. 6 is a bottom plan view of a supporting plate for the covers, showing also the clenching devices;

Fig. 7 is a side view of the supporting head for the covers and the clenching devices. 70

The invention is herein shown as applied to a head seaming machine, which consists of a framework 1, on which is mounted a seaming head 2, carrying seaming rolls 3. 75 This seaming head is rotated and operated from a shaft 4, which is moved up and down by a lever 5, and is rotated through the gear connection 6 from a shaft in the main frame 1.

The cans are fed underneath the seaming head by a drum feed 7. Said drum feed consists of a support on which the filled can bodies rest, and along which they may slide. The cans are moved along the support by the 80 drum 8, which is formed with a spiral thread 9. This thread is so wound on the drum as to move the filled cans first to a station where the floating contents of the can body may be depressed. During this action upon the contents, the can body remains at rest. The 85 thread 9 is formed with a non-pitched portion to allow this dwell in the filled can during the depression of the contents therein.

The filled can is then conveyed to a second 90 station where a cover may be applied and attached thereto, and again the filled can will pause in its movement during the action of the cover-applying means. The thread on the drum will again move the filled can along 95 underneath the seaming head, where it is held stationary during the seaming of the cover to the can body. This means for seaming the cover to the can body is shown and described in the patent granted to L. C. 100 Krummel September 21st, 1909, No. 934,921, and the feeding mechanism herein shown is fully described in the patent granted to L. C. Krummel and J. C. Taliaferro August 17th, 1909, No. 931,434. In view of these 105

110

patents, this seaming mechanism and the feeding mechanism therefor, will not be further described.

The cover-applying devices consist of a 5 supporting plate 10, which is formed with forwardly projecting guides 11. These guides 11 are attached to the under face of the plate 10, as shown in Figs. 6 and 7. The upper inner edges of the guides are recessed 10 at 12, as indicated in dotted lines in Fig. 7, to form a guideway for the covers. The covers are placed by hand on the guides 11, and may be slid along the guide to a point centrally underneath the supporting plate 15 10. This supporting plate 10 is threaded on to the lower end of a stem 13, which extends through a sleeve 14 mounted in a bearing 15, and at its upper end through a bearing 16. The bearings 15 and 16 are carried at the 20 outer end of a bracket 17, which is secured at 18 to the side wall of the frame 1.

At the lower end of the sleeve 14 is a head 19. A spring 20 surrounds the stem 13, and at one end engages the head 19, while the 25 other end of the spring is seated in a recess 21, formed in the upper face of the plate 10. The plate 10 is formed with two oppositely disposed recesses 22, in which are pivoted clenching fingers 23. These clenching fingers 30 are mounted on pivot pins 24, which are inserted in openings formed in the plate 10. A plurality of openings are provided, so that by shifting the pin 24, the clenching fingers may be positioned for different sized cans. 35 A spring 25 is seated in a pocket 26 in the inner wall of the plate 10, and bears against the clenching fingers and normally tends to move the same outward, and to hold the adjustable screw 27 carried by the clenching 40 fingers against the head 19.

The clenching finger near its lower end is formed with a groove 28. It will readily be seen that if the head 19 is moved toward the plate 10, that the clenching fingers will be 45 swung about their pivotal supports, and the lower ends thereof moved toward each other. If the head be moved in the opposite direction, or away from the plate 10, the springs 25 will move the clenching fingers so as to 50 carry the lower ends thereof away from each other.

The grooves in the clenching fingers, when the parts are in the normal position shown in Fig. 4, are in line with the guideways 12 in 55 the guiding members 11, so that when the cover is pushed along the guideways 12, it will be moved into the grooves in the clenching fingers.

An adjustable stop 29 is attached to the 60 plate 10, and limits the inward movement of the cover, so that when the cover is resting against the stop it will be centered relatively to the clenching fingers, and supported by said clenching fingers. The sleeve 14 is 65 provided with a grooved collar 30 at its up-

per end, which collar engages a forked lever 31 mounted on a rock shaft 32. The rock shaft 32 is formed with an arm 33, which is connected to a link 34. The link 34 at its upper end carries a roll coöperating with a cam 35 mounted on the cross shaft of the head-seaming machine, so that as the cross shaft of the seaming machine rotates, the rock shaft 32 will be oscillated in unison with the movements of the seaming head. 70 75

When the parts are in the position shown in Fig. 1, the spring 20 will force the plate 10 downward relative to the sleeve 14, until the stop pin 36 engages the upper side of the collar 30 (see Fig. 4). When the rock shaft 32 is oscillated, the sleeve 14 will move downward, carrying with it the plate 10 and the clenching fingers, together with the cover supported thereby. As soon as the cover is placed on the can body, any further downward movement of the plate 10 is prevented, and the downward movement of the head 19 through the continued oscillation of the rock shaft 32 will move the head 19 relatively to the plate 10, and swing the clenching fingers 80 which are supporting the cover by the outer edge of its flange, so as to bend the outer edge of the flange of the cover underneath the flange on the can body, as shown in Figs. 5 and 6, thus locking the cover to the can 85 body. 90 95

When the rock shaft 32 is moved in the opposite direction, the head 19 will first move away from the plate 30, as the spring 20 which is under tension, will tend to hold the plate 10 on the can body during the first upward movement of the sleeve 14. This separating of the plate 10 and the head 19, allows the springs 25 to throw the clenching 100 fingers out of contact with the flange on the cover, which releases the cover from the clenching head. The continued upward movement of the sleeve 14 will bring the stop pin 36 into contact with the collar 30, and raise the plate 10 from the can body, so that 105 the same may be moved forward and to the seaming station. 110

As a means for centering the can body underneath the cover plate and clenching devices, centering jaws 37 and 38 are provided, which engage the can body adjacent its upper end and properly center the same relative to these parts. These centering jaws are mounted on slides 39, which move back and forth in suitable guideways in brackets 40, which are attached to the supporting bracket 17. 115 120

The centering jaw 37 is connected by a link 41 to an arm 42, indicated in dotted lines in Fig. 3. The arm 42 is carried by 125 a rock shaft 43, which is formed with a second arm 44, connected by a link 45 to an arm 46 on the main rock shaft 32.

The centering jaw 38 is connected by a link 47 to an arm 48 on a rock shaft 49. 130

On the outer end of the rock shaft 49 is a second arm 50, which is connected by a long link 51 to an arm 52 on the rock shaft 43, so that as the rock shaft 43 oscillates, the 5 shaft 49 will be oscillated and move the centering jaw 38 in unison with the jaw 37. The connections with the jaws 37 and 38 are located between the rock shafts 43 and 49, and, therefore, these jaws will move in 10 unison in opposite directions.

The can body is carried by the drum feed underneath the cover-applying devices, and as the rock shaft 32 is oscillated to bring the 15 clenching fingers and supporting head downward to place the can cover on the can body, the centering jaws will be moved inwardly and engage the can body and properly center the same underneath the cover, so that the cover may be properly seated 20 in the can body and clenched thereto.

It is often desirable to force the floating contents in the filled can downward into the can body, so as to place the filled can in condition for receiving the cover. In order 25 that this may be accomplished in advance of the applying of the cover to the can body, the plunger 53 has been provided, which carries at its lower end a head 54, which is properly shaped to enter the filled can and 30 crowd the floating contents thereof downward into the can body. This plunger 53 is mounted to reciprocate in a bracket 55. A link 56 is attached to the upper end of the plunger 53, and at its upper end is se- 35 cured between the forked ends of an arm 57, which is fastened on the outer end of the rock shaft 32, so that as the rock shaft 32 oscillates to move the centering jaws and the head-applying devices in unison with 40 the movements of the seaming head, the plunger 53 is moved downward, so as to depress the contents of the can body into the filled can.

In the operation of the device, the filled 45 cans are placed one after another on the drum feed, and are carried along by the continuous movement of the drum 8. Filled cans will be first brought underneath the plunger 53, where the same will pause while 50 the plunger moves downward to crowd the contents of the can body into the filled can. The drum feed will then carry the filled can underneath the cover-applying devices. A cover is placed by the operator underneath 55 the clenching head. In this connection it is noted that while herein I have shown the covers applied by hand, it is obvious that automatic devices may be provided for feeding the covers from a stack one by one un- 60 derneath the clenching head.

The clenching head moves downward, carrying the cover therewith, and the centering jaws will move inward, so as to center the can body underneath the clenching head. 65 The cover is placed on the can body, and the

flange of the cover will be turned underneath the flange of the can body by the clenching fingers, at points diametrically opposite each other, so as to temporarily hold the cover seated in the can body. The drum feed will 70 then convey the can body with the head attached thereto after the clenching head has been withdrawn, to the seaming station, where again the can will pause while the seaming rolls finish the securing of the cover 75 to the can body.

It is obvious that minor changes in the details of construction and the arrangement of parts may be made, without departing from the spirit of the invention, as set forth 80 in the appended claims.

Having thus described my invention, what I claim as new and desire to secure by Letters Patent, is:—

1. A can closing machine including in 85 combination, a seaming head, cover-applying and clenching devices, a support for the filled cans, means for moving said seaming head toward and from said support, means for moving said cover-applying and clenching devices toward and from said support in unison with the means for operating the seaming head, and means for feeding the filled cans in succession to the cover-applying and clenching devices and the seaming 90 head.

2. A can closing machine including in combination, a seaming head, a cover-supporting device, clenching fingers carried by said cover-supporting device, said clenching 100 fingers being spaced from each other so as to clamp the cover to the can body at spaced intervals, a support for the filled cans, means for moving said cover-supporting device toward and from the support for placing a 105 cover on a filled can, means for operating said clenching fingers for clamping the cover to the can body, and means for feeding the cans in succession underneath the cover-supporting device and the seaming 110 head.

3. A can closing machine including in combination, a seaming head, cover-applying and clenching devices, a plunger for depressing the floating contents of the can, 115 means for operating the cover-applying and clenching devices and the plunger in unison with the seaming head, and a feeding device for feeding a filled can to the plunger, the cover-applying devices and the seaming head 120 in succession.

4. A can closing machine including in combination, a plunger for depressing the floating contents of the can, cover-applying and clenching devices, means for operating 125 said plunger and said cover-applying and clenching devices in unison, and means for feeding a filled can to the plunger and to the cover-applying and clenching devices in succession.

- 4
5. A can closing machine including in combination, a feeding device having devices for moving filled can bodies and for causing the same to dwell, a plunger, means 5 for operating the plunger to depress the contents in the can body while at one dwell, a cover-applying and clenching device, and means for operating the said cover-applying and clenching device to apply a cover to a 10 can body while at another dwell, a seaming head, and means for operating said seaming head to secure the cover to the can body while at a dwell. 15
6. A cover applying and securing means including in combination, means for supporting the can body, means for rounding up the can body, means for supporting a cover over the can body, means for placing the cover carried by the support on the can 20 body and turning the edge of the cover underneath the flange on the can body for clenching the cover to the can body. 25
7. A can closing machine including in combination, a seaming head, a cover-applying station having means for applying and clenching the covers to can bodies prior to presenting same to the seaming head, means for feeding the can bodies to the cover-applying and clenching means and to the 30 seaming head, said cover-applying and clenching means including means for supporting the cover, and means for placing the cover on the can body and clenching the cover at spaced intervals to the can body 35 while at the cover-applying station. 40
8. A cover applying and securing means including in combination, means for supporting the cover, means for feeding a can body underneath said support, a centering device for centering the can body underneath the cover, means for placing the cover carried by the support on the can body, and means for clenching the cover to the can body. 45
9. Cover-applying and clenching devices including in combination, a supporting plate, guides carried by said supporting plate for guiding the cover, clenching fingers carried by said supporting plate, a stem 50 on which said supporting plate is mounted, a head mounted on said stem, means for moving said stem and said head and means for giving the head a relative movement on said stem, for operating said clenching fingers. 55
10. Cover-applying and clenching devices including in combination, a supporting plate, guides carried by the supporting plate for guiding a cover, a stem on which said supporting plate is mounted, a sleeve mounted on said stem, a head carried by said sleeve, a spring interposed between said head and said plate, clenching fingers pivoted to said supporting plate, springs for normally forcing said clenching fingers outwardly, adjusting screws carried by said fingers and engaging said head, whereby when said head is moved relative to the supporting plate, the clenching fingers will be swung about their pivotal support. 60
11. Cover-applying and clenching devices including in combination, a supporting plate having oppositely disposed recesses, clenching fingers pivotally supported by said plate in said recesses, the lower ends of said clenching fingers being formed with a groove to receive and support a can cover, guides carried by the supporting plate in line with the grooves in the clenching fingers, and a stop for limiting the movement 75 of the cover and positioning the same centrally of said supporting plate. 80
12. Cover-applying and clenching devices including in combination, a feeding device, centering jaws for engaging and centering a can body, a supporting plate for a can cover, clenching fingers carried by said supporting plate, and means for moving said supporting plate up and down and for moving said centering jaws to center the can body underneath the cover on the supporting plate. 85
13. Cover-applying and clenching devices including in combination, a feeding device, a supporting plate, clenching fingers carried by the supporting plate, means for moving said supporting plate up and down to apply the cover to the can body and clench the same thereto, oppositely disposed centering jaws, and means for moving said centering jaws to center the can body underneath the cover prior to the placing of the cover on the can body. 90
- In testimony whereof I affix my signature, in presence of two witnesses.
